(57) CLAIM

The ornamental design for a supportive pouch for an undergarment, as shown and described.

DESCRIPTION

FIG. 1 is a top front perspective view of a supportive pouch for an undergarment, showing my new design;
FIG. 2 is a top rear perspective view thereof;
FIG. 3 is a front elevation view thereof;
FIG. 4 is a rear elevation view thereof;
FIG. 5 is a right-side elevation view thereof, the left-side elevation view being a mirror image thereof;
FIG. 6 is a top plan view thereof; and,
FIG. 7 is a bottom plan view thereof.

The broken lines showing the undergarment depict environmental subject matter that forms no part of the claimed design.

1 Claim, 4 Drawing Sheets
